United States Patent Office

Des. 228,793
Patented Oct. 23, 1973

228,793

CANDLE HOLDER

William C. Shumate, P.O. Box 2821,
Meridian, Miss. 39201

Filed Jan. 25, 1972, Ser. No. 220,729

Term of patent 14 years

Int. Cl. D26—01

U.S. Cl. D48—2

FIG. 1 is a perspective view of a candle holder showing my new design.

FIG. 2 is an elevational view of the opposite side of FIG. 1.

FIG. 3 is a top plan view thereof.

FIG. 4 is a bottom plan view thereof.

FIG. 5 is a perspective view of a second embodiment of my new design.

FIG. 6 is a side elevational view thereof.

FIG. 7 is a top plan view thereof.

FIG. 8 is a bottom plan view thereof.

I claim:

The ornamental design for a candle holder, as shown and described.
